United States Patent Office

Des. 220,721
Patented May 11, 1971

220,721

TURNING CENTER

Brooks Stevens, Fox Point, Wis., assignor to Kearney &
Trecker Corporation, West Allis, Wis.

Filed Jan. 22, 1970, Ser. No. 21,037

Term of patent 14 years

Int. Cl. D15—05

U.S. Cl. D54—6

Fig2

FIG 3

FIG. 4

FIG. 1 is a perspective view of a turning center showing the front and left side thereof illustrating my new design;

FIG. 2 is a front view in elevation of the turning center;

FIG. 3 is a left side view in elevation of the turning center; and,

FIG. 4 is a top plan view of the turning center. The right and rear sides, not shown, of the turning center being substantially plain.

I claim:

The ornamental design for a turning center, substantially as shown and described.
